UNITED STATES PATENT OFFICE

104,467

DESIGN FOR A SPOON OR OTHER ARTICLE OF FLATWARE

John P. O'Donnell, Hartford, Conn., assignor to
Gorham Manufacturing Company, Providence,
R. I., a corporation of Rhode Island

Application March 19, 1937, Serial No. 68,285

Term of patent 14 years

To all whom it may concern:

Be it known that I, John P. O'Donnell, a citizen of the United States of America, of 341 Washington Street, Hartford, Connecticut, have invented a new, original, and ornamental Design for a Spoon or Other Article of Flatware, of which the following is a specification, reference being had to the accompanying drawing forming part thereof.

Figure 1 is the obverse side of a spoon showing my new design, while Figure 3 shows the reverse side of the same spoon. Figure 4 is a cross-section of the spoon in Figure 1 on line 4—4, and Figure 2 is a side view.

I claim:

The ornamental design for a spoon or other article of flatware, substantially as shown.

JOHN P. O'DONNELL.
